UNITED STATES PATENT OFFICE.

BAPTIST E. BOYETT, OF TRIMBLE, TENNESSEE.

EXCHANGE-TABLE AND COMPUTING-MACHINE.

SPECIFICATION forming part of Letters Patent No. 627,715, dated June 27, 1899.

Application filed February 14, 1898. Serial No. 670,299. (No model.)

To all whom it may concern:

Be it known that I, BAPTIST E. BOYETT, a citizen of the United States, residing at Trimble, in the county of Dyer and State of Tennessee, have invented certain new and useful Improvements in Exchange-Tables and Computing-Machines; and I do hereby declare the following to be a full, clear, and exact description of the invention, such as will enable others skilled in the art to which it appertains to make and use the same.

This invention relates to exchange-tables and computing-machines, and has for its object to provide a simple, compact, and efficient device of the character referred to by means of which various difficult calculations may be made and the result ascertained in a short space of time.

The detailed objects and advantages of the invention will be pointed out in the course of the subjoined description.

The invention consists in an improved exchange-table and computing device embodying certain novel features and details of construction and arrangement of parts, as hereinafter fully described, illustrated in the drawings, and incorporated in the claims hereto appended.

In the accompanying drawings, Figure 1 is a plan view showing one side of the improved computing device. Fig. 2 is a similar view showing the reverse side. Fig. 3 is a longitudinal section through the complete device. Fig. 4 is a face view of one side of the rotatable disk. Fig. 5 is a similar view of the reverse side thereof.

Similar numerals of reference designate corresponding parts in the several views.

The improved computing device contemplated in this invention comprises a handle 1, which is slotted or bifurcated for the greater portion of its length to form two oppositely-located parallel arms 2, which are connected at their extremities by means of a transverse bolt or pin 3, forming the pivot or fulcrum upon which the rotatable portion of the device turns.

Mounted between the arms 2 are two thin plates 4 and 5, of metal or any suitable material, which are polygonal in shape or have a plurality of straight sides and provided with perforations or apertures, as hereinafter noted.

Between these two plates is mounted a rotatable disk 6, the periphery of which is notched, milled, or knurled to facilitate the turning of the same by hand. This disk forms an exchange and computing table and is provided upon opposite sides with numbers arranged in concentric circular rows, indicating in some instances pounds and in other instances dollars and cents.

The plate 4 is provided with several series of openings, each series being arranged in curved order. One series (indicated at 7) is laid off in different values, each opening or perforation representing a different value and each opening serving as an observation-aperture through which the figures or numerals on the adjacent side of the rotatable disk may be viewed. The prices marked on the perforations 7 relate to the retail price of flour. Another series 8 relates to the quantity or number of pounds of wheat and amount given in exchange from twenty-six pounds to thirty-six pounds per bushel. A third series (indicated at 10) relates to the quantity or number of pounds of bran given in exchange for wheat at ten, eleven, and twelve pounds per bushel. The fourth series on the plate 4 (indicated at 9) is laid off in prices which relate to the retail price of bran. The other plate 5 is provided near its center with two series of observation-apertures 11, which refer to the price of shelled corn per bushel. Another series (indicated at 12) relates to the exchange of shelled corn into meal, with one-fifth, one-sixth, or one-eighth off for toll. Another series 15 refers to the retail price of meal per bushel on a forty-six-pound-per-bushel basis. Another series 14 refers to retail price of meal on a basis of forty-eight pounds per bushel, whereas in the series 13 a fifty-pound-per-bushel basis is employed.

From the foregoing description it will be seen that the side indicated by 4 is for wheat, flour, bran, &c., while the plate 5 is for corn, meal, &c.

Commencing with the plate 4, 8' represents the wheat in pounds and 8 the amount of flour to be given per bushel in exchange for wheat, ranging from twenty-six to thirty-six pounds. 10 indicates bran to be given in exchange for wheat, ranging from ten to twelve pounds per bushel. The group 7 is the price

of flour, ranging from two dollars and fifty cents to six dollars per barrel. 9 is the price of bran from forty cents to eighty-five cents per hundred pounds.

5 For example, suppose A comes to mill with eight hundred and forty pounds of wheat and wants one barrel of one hundred and ninety-six pounds patent flour and balance straight. The miller is giving thirty-one pounds patent 10 or thirty-five pounds straight and eleven pounds bran for every bushel of wheat. First, turn disk till "840" pounds comes at opening 8', and by looking at "35" pounds in group 8 the miller will find amount due him to be four hundred and ninety pounds of flour, and from 15 group 10 it will be seen at eleven pounds that he is due one hundred and fifty-four pounds bran. Now turn disk till "196" comes to opening "31" pounds in group 8, and by looking at "35" pounds it will be seen that the equivalent of one hundred and ninety-six at thirty-one pounds is two hundred and twenty-one pounds at thirty-five pounds. Now deduct this amount (two hundred and twenty- 20 one pounds) from first amount (four hundred and ninety pounds) and the balance due him will be seen at two hundred and seventy-nine pounds.

To work group 9, say the producer is selling one-dollar bran while it is worth sixty-five cents per hundred. Turn disk until "100" comes to the dollar-sign (\$) in group 7. Then look at "65c." and the amount is found to be one hundred and fifty-three pounds. The 30 same rule governs group 7. Say the producer wants to sell five dollars' worth of flour while flour is worth three dollars and seventy-five cents per barrel. Turn the disk till "500" comes to the dollar-mark in group 7, and look at "#3.75" and observe the amount purchased to be two hundred and sixty-six pounds.

To illustrate the workings of plate 5: One dollars' worth of meal at sixty cents per bushel and forty-six pounds per bushel may 45 be found by turning disk till "100" comes to the dollar-sign (\$) in group 11. Then look at "60c." in group 15 and it will be seen that the amount required is seventy-six pounds. The same will work with group 14 or 15, also 50 with shelled corn in groups 11 and 11.

The remainder of the table is for exchange of corn. Say A comes to mill with five hundred and seventy-five pounds shelled corn and wants meal for same and the miller is taking one-sixth off for toll. He turns disk till "575" shows at *a* in group 16, and looks at " $\frac{1}{6}$ " off and finds he wants four hundred and seventy-nine pounds. The same is true with the one-eighth off or one-fifth off. Suppose, however, his corn is not shelled and he has ear-corn with shuck on nine hundred and thirty pounds. The miller turns the disk until "930" shows at *b* in group 12, and if it takes seventy-four pounds to make a bushel 65 he looks at "74" pounds and sees the amount seven hundred and three pounds, which can

readily be exchanged to meal at one-eighth, one-sixth, or one-fifth off. The same is true with seventy-two pounds or seventy pounds per bushel ear-corn.

70

16 designates a lock for the polygonal plates, the said lock being in the form of a block inserted in the crotch of the handle and secured by means of a pin or bolt 17. The locking-block 16 is of sufficient width to engage both 75 of the polygonal plates and is provided with a V-shaped edge, so as to receive and embrace the corners or angles of the plates. By removing the bolt 3 the polygonal plates may be correspondingly turned through a partial 80 rotation, so as to bring any desired angle or corner of the plates into engagement with the locking-block, when upon reinserting the bolt both plates are held locked in their proper relative position and prevented from turning. 85 This adjustment is provided in order to enable the table or series of openings used the most frequently to be brought into the most convenient position for reference.

From the foregoing description it will be 90 seen that I have provided a simple and efficient computing-table which will greatly facilitate the miller and farmer in determining how many pounds of one article should be given in exchange for a specified quantity of 95 another article.

It will of course be understood that the device described is susceptible of various changes in the form, proportion, and minor details of construction, which may accordingly be resorted to without departing from the principle or sacrificing any of the advantages of the invention.

Having thus described the invention, what is claimed as new, and desired to be secured 105 by Letters Patent, is—

1. In a computing device, a pair of polygonal plates arranged in parallel relation, but spaced apart and each provided with several sets of observation-openings, each set extending spirally, a handle connecting said plates, and means permitting the adjustment of said plates relatively to said handle, in combination with a rotatable disk journaled between the plates and provided upon opposite sides 110 with tabulated figures arranged in concentric circular rows and designed to be brought consecutively into view through said openings, the parts being so constructed that the inner disk may be turned independently of the 115 enclosing plates, substantially as described.

2. In a computing device, a pair of polygonal plates having a corresponding number of straight edges and angles or corners defined thereby, said plates being arranged in 120 parallel relation, but spaced apart and provided with observation-openings, and a bifurcated handle connecting said plates, in combination with a rotatable disk mounted between the plates and provided on opposite 125 sides with tabulated figures for exposure 130 through said openings, and a locking device

seated in the crotch of the handle and engaging both polygonal plates for holding the latter stationary, substantially as described.

3. In a computing device, a pair of polygonal plates having corresponding straight edges and angles or corners defined thereby, and a forked handle connecting said plates, in combination with a rotatable disk mounted between said plates, and a locking-block

10 seated in the crotch of the forked handle and

having a V-shaped edge whereby it is designed to receive and hold the corners or angles of both of the polygonal plates, substantially as and for the purpose described.

In testimony whereof I affix my signature 15
in presence of two witnesses.

BAPTIST E. BOYETT.
